UNITED STATES PATENT OFFICE.

MAXIMILIAN PAUL MILLER, OF COLLINGSWOOD, NEW JERSEY, ASSIGNOR TO WARREN WEBSTER & COMPANY, A CORPORATION OF NEW JERSEY.

STEAM-HEATING SYSTEM.

1,098,676.

Specification of Letters Patent.

Patented June 2, 1914.

Application filed December 8, 1910. Serial No. 596,198.

To all whom it may concern:

Be it known that I, MAXIMILIAN PAUL MILLER, a citizen of the United States, and a resident of Collingswood, Camden county, 5 State of New Jersey, have invented an Improvement in Steam-Heating Systems, of which the following is a specification.

My invention has reference to steam heating systems and consists of certain improvements which are fully set forth in the following specification and shown in the accompanying drawings which form a part thereof.

The object of my invention is to provide 15 a low pressure steam heating system with automatic means for returning the water of condensation into the boiler irrespective of any excessive pressures which may abnormally exist from any cause.

More particularly my object is to provide 20 a gravity system of steam heating with auxiliary power means for forcing the water of condensation from the returns into the boiler whenever the pressure in the boiler increases abnormally to such extent that the 25 normal possible static head of water in the returns will not be sufficient to return the water against said abnormal boiler pressure, the said power means being put into action 30 under the control of the static head, whereby the low pressure operates economically under normal conditions without the use of power means for returning the water to the 35 boiler and at the same time operates automatically to insure the return of the water to the boiler under abnormal conditions.

My invention consists of certain features 40 of construction for securing the above specified objects in a steam heating system, all of which are fully described hereinafter and more specifically defined in the claims.

In the drawings is shown diagrammatically an elevation of a steam heating system embodying my invention.

2 is a boiler and supplies steam to the radiators by a steam supply main 3 and branch pipes leading therefrom.

6 is one of the radiators, 5 is the branch steam pipe and 7 is the modulation or control valve.

4 is a main valve in the steam main, 9 is the return main and 8 the branch return leading from the radiator and discharging into the return main.

10 is a return trap in the branch return

for permitting the passage of water and air from the radiator into the branch return pipe while preventing or restricting the escape of steam, and this device may conform to any of such devices now upon the market 60 and of which there are numerous types better known as the thermostatic, float and motor types. Instead of such automatic traps, static valves may be employed as will be understood by those skilled in the art. The 65 return main 9 and all others of a similar nature may discharge into a receiver 11 where the condensation water may be collected and passed by pipes 12 and 13 into the boiler 2 by gravity. The receiver 11 is 70 located at a distance above the normal water level in the boiler and is provided with an air vent 28 and with a float 26 which rocks a shaft 25 to which is secured an arm 24 whose function will be hereinafter described. 75

16 is a pump of any suitable construction and is connected at its suction port with the return pipe 12 by a pipe 17; the discharge port of the pump is connected by a pipe 18 with the return pipe 13. The pipe 12 is also 80 provided with a check valve 14 at a point between the discharge pipe 18 and suction pipe 17. The pump is driven by a motor 19 which by way of illustration is shown as an electric motor. The current to this motor is supplied by circuits 20 and 22 and is 85 controlled by a switch 21 of any suitable construction. This switch is controlled by a chain 23 connecting with the arm 24 actuated by the float 26 of the receiving tank. 90

The operation of the apparatus will now be described:—Assuming that a normal low pressure, for example one-half to one pound, be in the steam boiler, the steam will be supplied under the control of the valve 7 95 to the radiators. The water of condensation produced in the radiators is returned to the boiler by the return pipe 9, receiver 11, return pipe 12 and pipe 13, and in passing from the pipe 12 to the pipe 13, it is passed 100 through a check valve 14. The static head in the pipe 12 insures the return of the water into the boiler against the pressure therein. Any water of condensation from the steam main 3 returns to the boiler by the drip pipe 15 which discharges into the pipe 13. This drip pipe 15 may be provided with a check valve 28 to permit water of condensation to flow to pipe 13 but prevent flow 105 of water from the pipe 13 upward through 110

said drip pipe 15. So long as the low pressure is maintained in the boiler, the water from the returns will return automatically by gravity. If now, from any 5 cause the boiler pressure suddenly rises to such a degree that the normal static head will not be sufficient to return the water from the returns, the motor 19 is automatically put into operation by this 10 increased pressure in the boiler exerted through the water column or static head and float and the pump 16 is then employed to positively force the water into the boiler. This action does not occur until the water 15 rises in the pipe 12 and within the receiver 11 sufficiently to operate the float 26 to actuate the switch 21 and thereby supply current to the motor 19. The check valve 14 prevents the pump being short circuited between its suction and discharge pipes. In 20 this way, the pump positively delivers the water into the boiler against the abnormal boiler pressure and continues to do so, so long as the water of condensation is made 25 to actuate the float. The pump should have a check valve which when the motor is at rest will not permit back flow of water from the boiler into the receiver through the pump. If a rotary pump is employed as 30 indicated, such a check valve may be located in the pipe 18 at 27.

This invention is especially useful in apartment houses and places where a janitor is required to attend to many duties aside from the steam heating and where accidental neglect might cause serious trouble from low water in the boiler aside from the inconvenience from defective steam heating.

I have shown the pump operated by an 40 electric motor because it is a simple and effective application, and current is usually supplied from the street main and hence requires no attention from the janitor, but I do not restrict myself to the use of an electric motor as any other type of motor, such 45 as steam, gas, water, etc., may be used if so desired. It is also to be understood that the controller 21 would be made of a suitable construction to suit the form of motor employed, but in any case, the controller would 50 be operated under the control of the water level in the receiver.

I have shown my invention in the form I prefer, but I do not limit myself to the details as they may be modified without departing from the spirit of the invention.

In this application no claim is made to the method of operation, as that will form subject matter of a separate application.

Having now described my invention what I claim as new and desire to secure by Letters Patent is:—

1. The combination of a boiler, a system of pipes leading from a higher level than 65 the water in the boiler and connecting with

the boiler for supplying it with water by gravity, means to prevent passage of water from the boiler backward into the system of pipes, power devices for forcing the water from the system of pipes into the boiler 70 against abnormal pressure therein, and automatic means under the control of the steam pressure in the boiler for putting the power devices into or out of operation.

2. The combination of a boiler, a system of pipes leading from a higher level than the water in the boiler and connecting with the boiler for supplying it with water by gravity, means to prevent passage of water from the boiler backward into the system of pipes, 75 power devices for forcing the water of condensation from the system of pipes into the boiler against abnormal pressure therein, and automatic means under the control of a static head of water above the water level in 80 the boiler supported by reason of the steam pressure in the boiler for putting the power devices into or out of operation.

3. The combination of a boiler, a system of pipes connecting with the boiler for supplying water to the boiler by gravity, a check valve to prevent passage of water from the boiler backward into the system of water supplying pipes, a pump having its suction and discharge connected with the 90 supply system of pipes respectively upon each side of the check valve for forcing the water from the system of pipes into the boiler against abnormal pressure therein, a motor for operating the pump, and automatic means under the control of the steam pressure in the boiler for putting the motor 95 into or out of operation.

4. A boiler and a water pipe for supplying water to the boiler by gravity, combined 105 with a check valve in the water pipe to prevent flow of water from the boiler backward into the water pipe, a pump connected in a by pass pipe in the water pipe about the check valve, a motor to operate the pump, 110 a controller for putting the motor into or out of operation, and means governed by abnormal pressure in the boiler to operate the controller.

5. A boiler and a water pipe for supplying water to the boiler by gravity, combined with a check valve in the water pipe to prevent flow of water from the boiler into the water pipe, a pump connected in a by pass pipe in the water pipe about the check 115 valve, a receiver connected with the water pipe at a level above the water level in the boiler, a motor to operate the pump, a controller for putting the motor into or out of operation, a float in the receiver and operated by the water therein governed by abnormal pressure in the boiler, and connecting means leading from the float to operate the controller.

6. A boiler and a water pipe for supply-

ing water to the boiler by gravity, combined with a check valve in the water pipe to prevent flow of water from the boiler backward into the water pipe, a pump connected in a by pass pipe in the water pipe and about the check valve, an electric motor to operate the pump, a controller and circuits to control the operation of the motor, and a float actuated device arranged in the water pipe

at a level above the normal water level of 10 the boiler for activating the controller.

In testimony of which invention, I hereunto set my hand.

MAX PAUL MILLER.
